(57) **CLAIM**

I claim the ornamental design for a cup holder pouch, as shown and described.

DESCRIPTION

fig. 1 is front elevational view of a cup holder pouch;
FIG. 2 is a right side view of the cup holder pouch (the left side view being a mirror image of the right side view);
FIG. 3 is a top view of the cup holder pouch wherein the cross hatch lines depict a different surface ornamentation;
FIG. 4 is a bottom view of the cup holder pouch; and,
FIG. 5 is a rear view of the cup holder pouch.
The dashed lines depict stitching and form no part of the design. The dash-dot-dash lines form no part of the design.
